CARBOY

Bryant H. Gardner, Springfield, and Frederick G. Towle, South Dartmouth, Mass.

Application October 27, 1951, Serial No. 17,137

Term of patent 14 years

(Cl. D58—12)

To all whom it may concern:

Be it known that we, Bryant H. Gardner, a citizen of the United States residing at Springfield, Commonwealth of Massachusetts, and Frederick G. Towle, a citizen of the United States residing at South Dartmouth, Commonwealth of Massachusetts, have invented a new, original, and ornamental Design for a Carboy, of which the following is a specification, reference being had to the accompanying drawing, forming a part hereof.

Fig. 1 is a top plan view of a carboy embodying our new design;

Figs. 2, 3, and 4 are, respectively, views from the front, rear and side of the carboy; and

Fig. 5 is a perspective view thereof.

We claim:

The ornamental design for a carboy, as shown.

**BRYANT H. GARDNER.
FREDERICK G. TOWLE.**
